BATTERY POST CONNECTOR

Alphonse Henry Eisler, Jr., New Orleans, La.

Application May 10, 1940, Serial No. 334,465

2 Claims. (Cl. 173—259)

This invention relates to certain new and useful improvements in battery post connectors.

The primary object of the invention is to provide a battery post connector especially designed for automobile batteries and of a construction to eliminate corrosion of the post and conductor attached thereto, the post of the battery having a polygonal head and the construction of the conductor being such that the same may be attached to a selected side of the polygonal head without unusual distortion of the conductor.

A further object of the invention is to provide a battery post connector of the foregoing character wherein the head of the post is of greater diameter than the post so that the conductor may be attached to the head laterally of the post carrying the head and being operative to eliminate the formation of corrosion at the connection.

With the above and other objects in view that will become apparent as the nature of the invention is better understood, the same consists in the novel form, combination and arrangement of parts hereinafter more fully described, shown in the accompanying drawing and claimed.

In the drawing:

Figure 1 is a top plan view of a battery post constructed in accordance with the present invention, a conductor cable attached thereto being fragmentarily illustrated;

Figure 2 is a side elevational view of the assembled post and conductor;

Figure 3 is a horizontal sectional view taken on line 3—3 of Figure 2, showing a head of polygonal formation carried by the upper end of the battery post, with crossed openings or bores in the head to facilitate selective engagement of the conductor with a side of the polygonal head;

Figure 4 is a vertical cross-sectional view taken on line 4—4 of Figure 1, showing the interfitting connection between the conductor and battery post head;

Figure 5 is a side elevational view of the post head with the post fragmentarily illustrated;

Figure 6 is an outer end elevational view of the conductor;

Figure 7 is a fragmentary side elevational view of the conductor; and

Figure 8 is a cross-sectional view taken on line 8—8 of Figure 7.

Referring more in detail to the accompanying drawing, it being understood that the battery post connector is especially designed for automobile batteries, the battery post is designated by the reference character 10 and carries at its upper end a laterally enlarged head 11 of poly-

gonal formation in plan view as illustrated in Figures 1 and 3, the same being illustrated as of triangular formation with three flat side walls 12, while the corners of the head are cut away to provide relatively short flat walls 13. It is to be understood that the head 11 may be attached to the upper end of the post 10 after the cell cover has been placed in position and the proper seal made about the post. Crossed holes or bores 14 extend horizontally through the head 11, a bore opening through each of the longer sides 12 and a shorter corner side 13 for the selective passage of an anchor bolt for securing a conductor cable to the head of the battery post 10.

The conductor, designated in general by the reference character 15, comprises the usual core of wires 16, shown in Figure 8, that has the usual insulation wrapping or covering 17, the insulation covering 17 of the conductor cable being cut away at the end thereof as shown in Figures 3 and 7 to expose the core of wires 16. A copper blade 18 has one end thereof embedded in the exposed conductor wires 16 as shown in Figures 3 and 7 and lateral flanges 19 carried by the embedded end of the copper strip or blade 18 are wrapped around the exposed core wires 16 as shown in Figure 8 with the outer ends of some of said core wires 16 bent backwardly over said flanges 19 for securing the copper strip or blade 18 to the conductor 15.

A metallic head 20 of general cup shape encloses the end of the conductor 15 and has a pocket 21 therein to accommodate the exposed ends of the core wires 16. A blade-like stem 22 projects outwardly from the closed end of the cup-shaped head 20 of the conductor and as shown in Figures 4 and 6, a longitudinally extending channel 23 is formed in each of the opposite sides of said blade-like stem. The copper blade 18 carried by the conductor body 15 is embedded in the blade-like stem 22 as shown in Figures 3 and 4 and opposite edges of said copper blade 18 are notched as at 18a to facilitate anchoring engagement with the blade-like stem. An opening 24 is formed in the outer end of the copper blade 18 of the conductor and registers with an opening 25 in the blade-like stem for the passage of a bolt for securing the conductor to the head of the battery post.

In attaching the conductor to the battery post 10, the blade-like stem 22 carried by the head 20 of the conductor 15 is selectively engaged with one of the flat sides 12 of the battery post head 11 with said flat sides 12 of the head interfittingly engaged with the adjacent channel por-

tion 23 of the blade-like stem. A clamping plate 26 is then placed in the other channel portion 23 and a screw bolt 27 is then passed through an opening in the clamping plate 26, the registering openings 24 and 25 and the aligned opening 14 in the battery post head 11, the headed end 28 of said bolt 27 being engaged with the clamping plate 26 as illustrated, while the threaded end 29 of said bolt passes through the opposite shorter corner or side 13 of the battery head for the reception of a lock washer 30 and a lock nut 31.

While there is herein shown and described the preferred embodiment of the invention, it is nevertheless to be understood that minor changes may be made therein without departing from the spirit and scope of the invention as claimed.

I claim:

1. In a battery post connector, the combination with a battery post having an enlarged head of polygonal formations defining a plurality of obtusely angled flat sides, said head having a plurality of intersecting bores extending trans-

versely thereof with the bores respectively opening at the flat sides intermediate the ends thereof, of a conductor having a head at one end thereof with a reduced blade-like stem projecting from the end of the head with the sides of the stem and adjacent end portions of the head defining obtusely angled faces, the stem being flatly engaged with a flat side of the post head and the adjacent end face of the conductor head being engaged with the adjacent flat side of the post head, said stem having an opening therein registering with a bore in the post head and a lock bolt extending through the registering opening and bore for retaining the conductor engaged with the battery post head.

2. A battery post connector as set forth in claim 1, wherein said stem has a channel formation in opposite sides thereof with a side of the battery post head received in one channel formation and a clamping plate in the other channel formation.

ALPHONSE HENRY EISLER, JR.
